(57) **CLAIM**

The ornamental design for an electrical connector, as shown and described.

DESCRIPTION

FIG. 1 is a front, top and right side perspective view of an electrical connector showing our new design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top plan view of FIG. 1; and,

FIG. 7 is a bottom plan view of FIG. 1.

The related contacts disposed in the tongue portion and in the upper wall and the bottom wall are similar to those of the conventional standard connector while the guiding post receiving cavity located at the right side of the tongue portion in the mating port provides better orientation, identification and the corresponding guiding and retention thereof in comparison with the conventional standard one.
